UNITED STATES PATENT OFFICE.

EDWARD J. FOGARTY, OF SOUTH BEND, INDIANA.

RAILROAD-CROSSOVER.

No. 831,782.

Specification of Letters Patent.

Patented Sept. 25, 1906.

Application filed January 26, 1906. Serial No. 298,050.

To all whom it may concern:

Be it known that I, EDWARD J. FOGARTY, a citizen of the United States, residing at South Bend, in the county of St. Joseph and State 5 of Indiana, have invented new and useful Improvements in Railroad - Crossovers, of which the following is a specification.

This invention relates to an improved paving for railway-crossings where a street or 10 road intersects a railroad-track; and the object generally is to provide a substantial pavement which will be continuous and flush with the top of the rails to permit pedestrians and vehicles to cross the track on a level 15 surface.

A further object is to provide a construction and arrangement that will relieve the paving-blocks from jar or vibration incident to the traffic on the track by the railway-cars, 20 and thus prevent displacement of the paving-blocks or their foundation.

These and other objects will be better understood by reference to the following description and to the accompanying drawings, 25 in which—

Figure 1 is a perspective view of a paving for a railway street-crossing constructed in accordance with my invention, with the paving-blocks and their foundations shown in 30 transverse section. Fig. 2 is a perspective view of one of the paving-blocks employed, and Fig. 3 is a perspective view of another paving-block.

Making renewed reference to the drawings, 35 1 designates the ties, which are laid in the road-bed as usual, and 2 designates the rails mounted on the ties, being secured thereto by any suitable track-fastening. Mounted on the ties on each side of the rail are bed-pieces 40 3 and 4. These bed-pieces consist of bars of cast-iron that extend parallel with the rails and have their inner sides shaped to conform to the web and base of the rail, there being a flange 5 at the bottom that projects beyond the base-flange of the rail and rests upon the 45 ties, as shown. These bed-pieces also have upward extensions 6, that flare slightly outwardly from the rail and surround the sides of the tread portion thereof, with their upper 50 surfaces flush with the tread of the rail, thus providing a chair for the rails, and preferably the extension 6 of the inner bed-pieces 4 is separated far enough away from the tread of the rail to provide a space or groove for the 55 flange of the wheels of the rolling-stock, whereby the said extensions serve as guard-

rails. The outer sides of these bed-pieces are concaved transversely, the concavity extending from the top to a shoulder 7 above the base of the flange 5, the said shoulder 60 forming a seat for the lower inner edge of the paving-blocks adjacent to the bed-pieces.

In Fig. 2 one of the paving-blocks 8 is shown as consisting of substantially a rectangular block with one side convexed, as at 65 9, and the opposite side provided with a longitudinal groove 10. The convexed face 9 is adapted to engage with the concaved face of the bed-piece, as shown in Fig. 1, and the groove 10 is adapted to receive a tongue 11 of 70 an adjacent block 12, whose opposite face is provided with a similar longitudinal groove 13 to receive the tongue of another block. I prefer to have the first two or three rows of 75 blocks adjacent to the bed-pieces provided with these tongues and grooves; but as this is an expensive construction the blocks may be of the plain type with straight flat sides, inasmuch as any jar or vibration incident to the traffic on the rails will not be communicated to the blocks near the center of the track or at any great distance from the rails, and therefore the blocks are not liable to be 80 dislodged from their foundation; but in some instances it may be advisable to employ the 85 tongue-and-grooved blocks throughout the pavement, while in other instances the tongue-and-grooved blocks may be entirely dispensed with.

The paving-blocks are preferably laid upon 90 a foundation 14 of cement, which is filled in between the ties and over the same, with its upper surface above the ties, so that the foundation for the paving-blocks is entirely independent of the foundation for the ties 95 and rails and bed-pieces, and thus the strains and vibrations upon the rails and bed-pieces are not communicated to the paving-blocks, but to the ties, as usual.

From the description thus far given it will 100 be seen that each rail is supported and partially inclosed by a chair constituted by the bed-pieces 3 and 4, which not only supports the rails, but also receives the strain and vibration incident to the traffic thereon, and, 105 further, that such strains are communicated to the ties and not to the cement foundation for the paving-blocks or to the latter. Furthermore, any lateral vibrations of the bed-pieces incident to vehicles crossing the track 110 or the rolling-stock upon the rails will not tend to dislodge the paving-blocks adjacent

to said bed-pieces because of the contiguous curved faces of the bed-pieces and the blocks 8 adjacent thereto, the elimination of such dislodgment being augmented by the groove-and-tongue connection of the blocks, though, as before stated, these may be omitted without departing from the principle of my invention. It will also be seen that the blocks 8 adjacent to the bed-pieces cannot move 10 downwardly, even should the cement foundation fall or weaken, inasmuch as the inner lower edge of said blocks engages with the shoulder 7 of each bed-piece, which shoulder is flush with the foundation for the blocks, 15 and the blocks cannot be moved upwardly because of the interlocking connection emanating from the curved contiguous faces and tongue-and-grooved connection.

Having thus described my invention, what 20 I claim, and desire to secure by Letters Patent, is—

1. The combination with the ties and the rails, of bed-pieces mounted on the ties and engaging the rails on opposite sides thereof, a bed or foundation laid between and over the ties with its upper surface above the ties, and paving-blocks laid upon said foundation between the bed-pieces.

2. The combination with the ties and rails, 30 of bed-pieces mounted on the ties and engaging the rails on opposite sides thereof, and having their outer faces concaved, a foundation laid between and over the ties with its upper surface above the ties, paving-blocks 35 laid upon said foundation between the bed-pieces, the paving-blocks adjacent to the bed-pieces having their contiguous faces convexed and fitted into the concavity of the bed-pieces, substantially as described.

3. The combination with the ties and the

rails, of bed-pieces mounted on the ties and engaging the rails on opposite sides thereof and having their outer faces concaved and also provided with a base-flange which rests upon the ties and provides a shoulder at the bottom of the concaved face, paving-blocks laid between the bed-pieces, the paving-blocks adjacent to the bed-pieces having convexed faces engaged with the concaved face of the bed-piece and resting on the shoulder above the flange of the bed-piece, substantially as described. 45

4. The combination with the ties and the rails mounted thereon, of bed-pieces mounted on each side of the rail and having base-flanges engaged with the ties, the inner bed-pieces having upward extensions spaced from the tread of the rail to constitute guard-rails, a bed or foundation laid between and over the ties with its upper surface above the 60 ties and flush with the base-flanges of the bed-pieces, paving-blocks mounted upon said foundations and having tongue-and-grooved connections with each other, the paving-blocks contiguous to the bed-pieces 65 partially resting upon the base-flanges thereof, substantially as described.

5. The combination with the ties and rails, of bed-pieces mounted on the ties and engaging the rails on opposite sides thereof, paving-blocks interlocking with said bed-pieces, and a bed or foundation to support said paving-blocks.

In testimony whereof I affix my signature in presence of two subscribing witnesses. 75

EDWARD J. FOGARTY.
